UNITED STATES PATENT OFFICE.

LEROY G. GATES, OF BAKERSFIELD, CALIFORNIA, ASSIGNOR TO STANDARD OIL COMPANY, OF SAN FRANCISCO, A CORPORATION OF CALIFORNIA.

DEEP-WELL PUMP.

Application filed February 25, 1925. Serial No. 11,487.

My invention relates to double acting pumps especially adapted for use in pumping deep wells.

The principal object of my invention is to provide a simple and practicable double acting pump of such size that it may be lowered into a well. This limitation in regard to size renders it practically necessary to use a single cylinder pump, in which the piston works during both its up and its down stroke. The advantages of a double acting pump are obvious to those skilled in the art. It is more efficient than a single acting pump, for the reason that no power is wasted in stopping and starting the column of well fluid in the discharge tubing string at each stroke, the flow of such fluid being practically continuous; and in the case of very deep wells, wherein the weight of the fluid column is relatively great, the saving in this regard is considerable. Moreover, a double acting pump, to raise the same quantity of fluid in a given time as a single acting pump, requires only half as much force to move its piston; therefore the pump can be made much smaller, since the power is applied practically continuously, instead of intermittently with equally long periods of practical rest. This becomes extremely important in deep well pumps on account of the necessarily small dimensions, since the bearings and moving parts can be made relatively large in proportion to the load. Finally, the practically continuous flow of a double acting pump produces a minimum of turbulence in the fluid stream, thereby attracting less sand from the well into the pump intake, and, in the case of oil wells, producing the minimum of troublesome water emulsion.

Another object of my invention is to provide a pump in which the destructive effects of sand in the pump itself are reduced to a minimum. A still further object is to provide a double acting pump having a minimum number of valves, which operate no more often than the corresponding valves of a single acting pump.

My invention is herein illustrated and described as embodied in a deep-well pump, but it is to be understood that it may be adapted, without material change to other uses. Moreover, the form and construction may be varied from that shown and described herein, within the limits of the

claims hereto appended, without departing from the essential features of the invention as set forth in said claims.

With this in view my invention will now be fully described with reference to the accompanying drawing, wherein—

The figure is a longitudinal section of a deep-well pump embodying my said invention.

In the drawing, the reference numeral 1 designates a pump cylinder or barrel, and 2 is a tubular plunger working therein. The intake of the barrel 1 is at its lower end, and is controlled by one or more suitable check valves 3. Only one such valve is shown but it is obvious that the number thereof is immaterial. The lower end of the hollow plunger 2 is provided with a travelling valve 4, which constitutes the discharge valve of the pump.

In the drawing I have shown a construction adapted for operation by means of sucker rods or other mechanism capable of exerting force in only one direction, i. e. upwardly. A tubular housing 1' is extended from the upper end of the barrel 1, and a suitable compression spring 5' is contained within said housing and adapted to force the plunger 2 downwardly by pressure against its upper end. A suitable tension member, shown as a rod 6', which is understood to be attached to the lower end of the sucker rod string, not shown, is secured to the plunger 2, preferably by being connected with the cage 4' of the traveling valve 4. Said rod 6' supplies the force for driving the plunger 2 upwardly and for compressing the spring 5', and said spring then supplies the force for moving said plunger downwardly. Inasmuch as the plunger 2 works upon both strokes, the spring 5' must be sufficiently powerful to handle its share of the load, and the force exerted upon the rod 6' on the up-stroke must be approximately twice that necessary to lift said plunger, in order to compress said spring at the same time.

The plunger 2 surrounds and slides upon a fixed tube 8, which is secured to and extends downwardly from the upper end or head 9' of the spring housing 1', and communicates with the tubing string 10' for conducting the pumped fluid to the surface. The lower end of the fixed tube 8 is open to the interior of the plunger 2, as shown.

Suitable packing, of any desired nature, is provided in the upper portion of the barrel 1, as shown at 11, to make a tight fit upon the plunger 2. Said plunger is likewise provided interiorly, with suitable packing 12 at its upper portion, to prevent leakage between it and the fixed tube 8. The interior of the barrel 1 is provided at its upper end with a portion of reduced diameter, in which the packing 11 is situated, and below such reduced portion, the base of said barrel is of slightly increased diameter, to provide a clearance, shown at 13, between it and the plunger 2. Similarly, the interior of said plunger is provided at its upper end with a portion of reduced diameter, in which the packing 12 is situated, and below such reduced portion, the bore of said plunger is of slightly increased diameter to provide a clearance 14 between it and the fixed tube 8. The clearance spaces 13 and 14 prevent the cutting of the surfaces of the barrel, plunger and tube by sand, by permitting such sand to settle, and such settling of the sand keeps it away from the packing 11 and 12, thereby preventing wear thereupon, and further preventing cutting of the outer surfaces of the plunger and the fixed tube.

The operation of my pump will be apparent from the foregoing description and the drawing. Assuming the barrel 1 to be full, the down stroke of the plunger 2 displaces a quantity of fluid equal to the volume or effective displacement of said plunger, such quantity of fluid being forced up through the discharge valve 4 into said plunger, and of this fluid an amount equal to the effective displacement of the plunger 2 less that of the fixed tube 8 is forced up through said tube and into the tubing string 10'. The up stroke of the plunger 2 draws a fresh charge of fluid into the barrel 1, and forces the fluid contained within said plunger out through the fixed tube 8 and the tubing string 10'.

Thus fluid is forced up, or discharged, upon both the up and down stroke, and by properly relating the inside and outside diameters of the plunger 2, and the outside diameter of the fixed tube 8, the relative quantities of fluid pumped during the two strokes can be suitably proportioned to supply a practically constant flow.

It is to be noted that the double action of my pump, i. e. its ability to displace fluid upon the down as well as the up stroke, depends upon the fact that the upper end of the tubular plunger is not exposed to the pumped fluid. There is, therefore, no negative displacement of fluid by the upper end of the plunger to balance or offset the positive displacement of its lower end within the barrel 1, as is the case in the ordinary types of hollow well pump plungers, which work only upon the up stroke. The only negative

displacement which does occur on the down stroke and which only partially offsets the positive displacement of the plunger within the barrel is that caused by the fixed tube 8 within said plunger, but by making the wall 70 of the plunger sufficiently thick in proportion to the outside diameter of said tube, such negative displacement becomes relatively small in proportion to the positive displacement of the plunger within the 75 barrel.

In other words, the double action of my pump does not depend upon the displacement of a solid piston reciprocating within a cylinder in the usual manner, but is accomplished by means of three concentric tubes, the inner and outer tubes, i. e. the fixed tube 8 and the barrel 1 being stationary while the middle tube, i. e. the plunger 2, reciprocates in the manner of a piston. The pumping action on the up stroke is the result of the upward movement of the liquid filled plunger tube 2, together with the check valve 4 which prevents the return of the liquid to the barrel 1. The pumping action 85 on the down stroke is due to the displacement of liquid within the barrel 1 by the mass of the plunger tube 2, the check valve or valves 3 preventing the return of the liquid into the well. 90

It is also to be noted that my plunger construction lends itself particularly well to the incorporation of the anti-sanding feature described above.

Not only does the double action of the plunger result in less turbulence of the well fluid at the intake, thereby causing less sand to be drawn into the barrel than would be the case in a single acting pump, but by providing the clearance spaces 13 and 14, and by 100 positioning the valves at the lower ends of the barrel and plunger respectively, such sand as is drawn into the barrel settles away from the portions of the pump in which it might do harm, i. e. the rubbing surfaces in 105 the regions of the packings 11 and 12, and is carried out in the fluid stream through the central tube 8. 110

Finally, it should be noted that there is but one set of valves, comprising one inlet 115 and one discharge, and that these valves operate only once for each complete, i. e. up and down, stroke, or no more often than in the ordinary single acting pump.

I claim:

1. A well pump comprising a barrel having a fluid inlet at its lower end; a tubular plunger operable in said barrel; a discharge valve carried in the lower end of said plunger; a fixed member extending into said plunger from its upper end and having a fluid discharge passage in communication with the interior thereof; a spring surrounding said fixed member and acting against the upper end of said plunger to move the 125 130

same downwardly; and a tension member extending through said fixed member and connected with the plunger in the region of its lower end for moving said plunger upwardly.

2. A well pump comprising a barrel having a fluid inlet in the region of its lower end; a tubular plunger operable within said barrel, said plunger having a shoulder above the upper end of said barrel; a fixed tubular member extending into said plunger from its upper end for conducting the pumped fluid therefrom; a tension member extending through said fixed tubular member and connected with said plunger for lifting it; and a spring surrounding said fixed tubular member and bearing against the shoulder of said plunger for moving it downwardly.

3. A well pump comprising a barrel hav-

ing a fluid inlet in the region of its lower end; an extension rising from the upper end of said barrel and provided with an upper head; a hollow plunger operable within said barrel and provided with a shoulder lying within said extension; a fixed tubular member secured to the upper head of said extension and extending into said plunger for conducting the pumped fluid therefrom; a tension member extending through said fixed tubular member and connected with said plunger for lifting it; and a spring surrounding said fixed tubular member and positioned within said extension between the head thereof and the shoulder of said plunger for moving the latter downwardly.

In testimony whereof I have signed my name to this specification.

LEROY G. GATES.
